UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

DESIGN FOR A GLOBE OR SHADE HOLDER.

SPECIFICATION forming part of Design No. 23,893, dated December 25, 1894.

Application filed October 8, 1894. Serial No. 525,302. Term of patent 7 years.

To all whom it may concern:

Be it known that I, LEWIS J. ATWOOD, a citizen of the United States, residing at Waterbury, in the county of New Haven and State of Connecticut, have invented a new 5 Design for a Globe or Shade Holder, of which the following is a specification.

The leading feature of this holder for globes or shades consists in the design of the holder 10 ring with scalloped upper edge and corrugations.

In the drawings, Figure 1, is an elevation partially in section, and Fig. 2, is a plan showing part of the ring.

The upper edge 2, of the ring holder is made 15 of a series of scallops and there are corresponding corrugations 3, in the rim of the holder and at 4, in the base of such holder.

The inner edge of the holder ring is shown 20 as plain at 5.

I claim—

The design of the ring holder for globes or shades substantially as shown and described.

Signed by me this 4th day of October, 1894.

L. J. ATWOOD.
